UNITED STATES PATENT OFFICE.

JAMES A. FIELDS AND JESSIE J. WITTE, OF SAN ANTONIO, TEXAS.

TIRE-CHAIN.

1,334,363.

Specification of Letters Patent. Patented Mar. 23, 1920.

Application filed December 23, 1918. Serial No. 268,017.

To all whom it may concern:

Be it known that we, JAMES ALBERT FIELDS and JESSIE JAMES WITTE, citizens of the United States, residing at San Antonio, 5 in the county of Bexar, State of Texas, have invented a new and useful Tire-Chain, of which the following is a specification.

This invention relates to anti-skid chains for pneumatic tires, one of the objects of 10 the invention being to provide a chain which will not only prevent skidding, but will also grip the road surface to such an extent as to increase the tractive power of the vehicle.

Another object is to provide a device of 15 this character which can be applied easily and quickly without the use of any special tools.

A still further object is to provide an anti-skid device the chains of which are so connected as to have sufficient relative movement to avoid stretching and breaking and to render them self adjusting to properly 20 distribute the strains.

With the foregoing and other objects in 25 view which will appear as the description proceeds, the invention consists of certain novel details of construction and combinations of parts which will be hereinafter more fully described and pointed out in the claim, 30 it being understood that various changes may be made in the construction and arrangement of the parts without departing from the spirit or sacrificing any of the advantages of the invention as set forth in the 35 appended claim.

In the accompanying drawings the preferred form of the invention has been shown.

In said drawings

Figure 1 is a plan view of a portion of 40 the device.

Fig. 2 is an enlarged side elevation of a fastener and the adjacent portions of the side chain.

Fig. 3 is a plan view of a center ring and 45 portions of the diverging diagonal chains.

Fig. 4 is a plan view of the structure shown in Fig. 2.

Fig. 5 is a perspective view of one of the fastening levers.

Fig. 6 is an enlarged view of one of the 50 side connections between the chains.

Referring to the figures by characters of reference, 1 designates the side chains of the device, said chains preferably being 55 made of flat cut links although it is to be understood that the chains can be of any

other construction desired. One of the end links of each side chain engages an eye 2 formed at one end of a short stem 3 and extending at an angle therefrom. An arm 4 extends from the other end of the stem at right angles thereto and is adapted normally to lie parallel with the adjacent portion of the chain 1 and to be held thereto by a ring 5. When the arm is thus located with 60 its stem 3 extended through the other end link of the chain 1 it will fasten the ends of the chain together as shown particularly in Fig. 4.

Connected to the side chains 1 at regular 70 intervals are rings 6, and the corresponding rings on the two chains are connected by cross chains 7. In the centers of the spaces defined by the chains 1 and 7 are rings 8. To these rings are connected the end links 75 of diagonal chains 9 each of which extends from one ring 8 through one ring 6 and thence to the next adjoining ring 8. As shown in Fig. 6 chain 9 has one link extending through the ring 6 and thus has 80 movement relative to the ring 6 substantially equal to the length of the link there-in. The chains 9 are not connected to the rings 6 engaged by the end chains 7. Instead short diagonal chains 10 connect these 85 end rings 6 to the adjacent rings 8.

In using the device the same is placed on an inflated tire in the usual way, the rings 5 first being disengaged from the arms 4 and said arms extended outwardly at angles 90 from the chains 1. The free ends of said chains 1 are then slipped onto the arms 4 and said arms swung inwardly about their connections with the chains at eyes 2 until the links have slid along the arms 4 and 95 onto the stems 3. The arms 4 are thus brought parallel with the chains 1 and are held thereto by bringing the rings 5 into engagement with the arms. Thus the side chains are securely fastened to the tire and 100 the cross chains 7 and diagonal chains 9 and 10 are caused to rest on the tread portion of the tire. The chains 7, 9 and 10 cooperate to prevent the tire from slipping, thereby increasing the tractive power, while skidding is prevented by the diagonal chains 9 and 10. Because of the slidable connections between the chains 1 and 9 the device can stand greater strains than where the connections are positive, because the relative 110 movement permits a yielding action which will prevent breakage. Because of the sym-

metrical arrangement of the chains the device will be as efficient during the backward movement of the wheel as during the forward movement thereof.

What is claimed is:—

A chain attachment for tires including side chains, rings engaging the side chains at regular intervals, cross chains connecting the rings and dividing the space between 10 the side chains into separate rectangles, rings disposed at the centers of the spaces between the side and cross chains, and a chain extending loosely through each of the rings on the side chains and secured

at its ends to the rings at the centers of the 15 adjacent rectangular spaces.

In testimony that we claim the foregoing as our own, we have hereto affixed our signatures in the presence of witnesses.

JAMES A. FIELDS.
JESSIE J. WITTE.
